ATTORNEYS

UNITED STATES PATENT OFFICE.

HARRY DORNIN WETHLING, OF ORANGE, NEW JERSEY.

ELECTRIC LOCK.

1,425,428.

Specification of Letters Patent. Patented Aug. 8, 1922.

Application filed February 9, 1921. Serial No. 443,661.

To all whom it may concern:

Be it known that I, HARRY D. WETHLING, a citizen of the United States, and resident of Orange, in the county of Essex and State 5 of New Jersey, have invented a new and Improved Electric Lock, of which the following is a full, clear, and exact description.

My invention relates to electric locks, and aims to provide certain new and useful improvements in connection with a device of 10 this character, and is particularly applicable in connection with the electrical system of an automotive vehicle, although the same may readily be utilized in association with 15 any desired circuit.

It is well appreciated that it has been customary to resort to a conventional key lock switch when it has been desired to open a circuit, and to guard against the closing of 20 the same by unauthorized persons.

Considerable difficulty has been experienced in connection with this expedient, in view of the fact that a key must necessarily be carried at all times by the authorized 25 person, aside from the fact that the lock is liable to become inoperative so that great delay is experienced in closing the circuit.

With this in mind, I have constructed a lock for a circuit which may readily be 30 operated to close the circuit by those persons who are authorized to operate the same and by means of which it will be virtually impossible for an unauthorized operator to succeed in closing the circuit.

35 A further object of my invention is the provision of a lock of this type which does not necessitate the carrying of a key to permit of its being operated.

Another object of my invention is to 40 provide certain improved construction, as well as a new combination of elements, over my prior application for a lock, Serial #309,365 filed July 9, 1919.

Further objects of my invention will appear in the annexed specification and drawings which latter present one practical embodiment of my invention, and in which—

Figure 1 is a plan view of a lock embodying my improved construction.

50 Figure 2 is a plan view similar to Figure 1, but showing the upper part of the lock casing removed.

Figure 3 is a sectional side view taken along the line 3—3 of Fig. 1 and in the 55 direction of the arrows, and

Figure 4 is a somewhat diagrammatic view illustrating the operation of the lock.

In connection with my prior application previously referred to, I propose to utilize the combination of a permutation element 60 serving to effect the turning of a valve, or valves for preventing a flow of fluid through a pipe line. A lost motion driving action was provided between the operating member and valve, so that an operator might be capable of opening the valve and subsequently turning the actuating member (within certain limits) so that an unauthorized person would be incapable of reading the proper setting of the parts 70 which would effect an opening of all the valves.

Although, the structure produced in connection with my prior application, has proven of great value in certain adaptations, it has been found that an expert operator is capable of manipulating the actuating element with such delicacy as to be capable of ascertaining when the lost motion ceases, and a coupling between the 80 parts takes place, thus rendering it within the limits of possibility to effect an opening of the lock on the part of an unauthorized person.

Thus this invention contemplates over- 85 coming this defect in that it will be virtually impossible for an unauthorized person to ascertain when a coupling of the elements is effected.

A further object of this invention forming the subject matter of this application, is to provide a member in the element of a switch, capable of cooperating with the lock, so that the circuit may be opened, and be guarded against unauthorized closing, it 95 being understood, however, that the actuating element illustrated is not necessarily limited for utilization in connection with an electrical circuit.

With the foregoing in mind, reference is 100 had to Figures 1 and 3, in which the reference numeral 5 indicates the cover of the body or lock, into which lead 6 of the circuit to be locked extend. Rotatably associated with the body of the casing 5 are 105 rods or other suitable elements 7 carrying actuating elements 8 permitting of their manual rotation. Also a plurality of dials corresponding in number to the number of rods utilized, are provided upon the upper 110 face of the casing 5, such dials being indicated by the reference numeral 9, and a pointer or other suitable element 10 is affixed to each of the rods 7, and serves to

indicate the position of the parts to the operator.

It is to be noted that the rod 7 is continued through the body of the casing 5 in the form of a reduced portion or stem 11, and the whole is retained in proper position by any suitable means, such as a spring 12 co-operating with a washer or flange 13 affixed to each of the stems 11.

10 In connection with the foregoing, it is to be noted that contrary to my conventional construction, each of the above elements is preferably constructed of insulating material, and it is to be noted that the stems 11 co-operate with the openings formed in the casing 5 for their reception, in such a manner as to necessitate the expenditure of a relatively great amount of force to effect a turning of the same for a purpose herein-after more fully specified.

Referring more particularly to Figures 2 and 3, it will be seen that the leads 6 are continued within the body of the casing in the form of wires or rods 14, having a plurality of gaps corresponding in number to the number of dials provided.

25 In each of these gaps or openings a rotatable switch element 15 is mounted, and the stem preferably carries a pair of springs 16 in electrical contact with each other, which springs serve to press the balls 17 outwardly and into intimate contact with the ends of the leads or rods 14.

Also it will be noted that the contact elements or balls 17 are preferably arranged at an angle of 90 degrees to each other, for a purpose hereinafter more fully specified, and a lug 18 is affixed to each of the elements 15, and extends into the path of travel of 40 the rod 19 affixed to the inner end of each of the stems 11.

Thus it will be seen, incident to the relatively stiff turning permitted on the part of the rod 7, that it will be impossible for an operator to ascertain that point at which contact is effected between the elements 18 and 19 so that it would be impossible to tamper with the switch in this respect.

Further, by virtue of the disposition of 50 the contact elements 17 at right angles to each other, or in any other position than diametrically opposite one another, it will be necessary to turn each of the bodies 15 to the correct position, and incident to the thickness of the elements 18 and 19, the rods 55 7 will have to be turned in that direction for which they were set to effect a closing of the circuit.

Thus, reference being had to Figure 4, it 60 will be seen that I have indicated the closing position of the switch, as being identified by the reference character 9, and in full and

dot and dash lines I have indicated the correct position which the parts will assume upon the switch being turned, as has been 65 shown by the arrow indicating a clock-wise turning. Further, upon the parts being turned in an anti-clock wise direction, as has been indicated by the dotted arrow, it will be appreciated that the switch will have 70 its elements moved to the position indicated solely in dotted lines, at which it will be seen that it would be impossible to effect a closing of the circuit despite the fact that the pointer 10 was registering with the 75 proper reference character 9.

From the foregoing it will be seen that I have provided a lock adapted to co-operate with a switch, and by means of which all of the objections of my invention as set forth 80 in the preamble will be accomplished, and it will further be understood that numerous modifications of structure might readily be resorted to without in the least departing from the spirit of my invention, which I 85 claim as:

1. An electric lock including a casing, an electrical conductor within said casing, switches interposed within said conductor, said switches each including a freely movable body, means associated with said body for contacting with the end of said conductor to close the circuit, operating elements for said switches, stems secured to said operating elements and extending through said 95 casing, means associated with each of said stems for rendering the same capable of being coupled with the body of the switch, and means co-operating with said stems to cause the same to offer resistance to being 100 operated.

2. An electric lock including a casing, an electrical conductor within said casing, switches interposed within said conductor, said switches each including a freely movable body, means associated with said body for contacting with the end of said conductor to close the circuit, operating elements for said switches, stems secured to said operating elements and extending through said 105 casing, a flange member associated with each of said stems, a spring interposed between each of said members and said casing whereby to cause said stem to offer resistance to being operated.

3. An electric lock including a casing, an electrical conductor disposed within said casing, switches interposed within said conductor, lugs associated with the body of each of said switches, stems associated with the casing and rods mounted upon said stems and being capable of engagement with said lugs.

HARRY DORNIN WETHLING.
